UNITED STATES PATENT OFFICE.

NORMAN LIPSKY, OF NEW YORK, N. Y., ASSIGNOR TO HALCOLITE COMPANY, INC.,
A CORPORATION OF NEW YORK.

DESIGN FOR A LIGHTING-FIXTURE WALL BRACKET.

Application filed November 5, 1927. Serial No. 24,018. Term of patent 7 years.

To all whom it may concern:

Be it known that I, NORMAN LIPSKY, a citizen of the United States of America, and a resident of the city, county, and State of New York, have invented a new, original, and ornamental Design for a Lighting Fixture Wall Bracket, of which the following is a specification, reference being had to the accompanying drawing, forming a part hereof.

The single figure in the drawing is a front elevational view of the lighting fixture wall

bracket. A fragment of the surface ornamentation of the lighting fixture wall bracket is illustrated in the upper left hand corner of the figure, it being understood that the remainder of the surface of the wall bracket is similarly treated.

I claim:

The ornamental design for a lighting fixture wall bracket substantially as shown and described.

NORMAN LIPSKY.
